UNITED STATES PATENT OFFICE.

LEONARD D. SOUBIER, OF TOLEDO, OHIO, ASSIGNOR TO THE OWENS BOTTLE COMPANY,
OF TOLEDO, OHIO, A CORPORATION OF OHIO.

APPARATUS FOR FEEDING MOLTEN GLASS.

Application filed May 17, 1923. Serial No. 639,607.

To all whom it may concern:

Be it known that I, LEONARD D. SOUBIER, a citizen of the United States, residing at Toledo, in the county of Lucas and State of 5 Ohio, have invented new and useful Improvements in Apparatus for Feeding Molten Glass, of which the following is a specification.

My invention relates to glass feeders for 10 producing charges or gobs of molten glass and delivering them to molds. An object of the invention is to provide a practical form of feeder particularly adapted for producing individual charges or masses of 15 comparatively large size.

Other objects of the invention will appear hereinafter.

In the accompanying drawings:

Figure 1 is a sectional elevation of glass 20 feeding apparatus constructed in accordance with my invention.

Figure 2 is a sectional plan view at the plane of the line II—II on Figure 1.

Figure 3 is a front sectional elevation of 25 the apparatus.

Figure 4 is a similar view of a portion of the apparatus, but with the parts in a different position.

The glass 10 is continuously supplied 30 from a furnace 11 to a forehearth or boot extension 12. The glass issues from an outlet opening 13 formed in a bushing 14 in register with an opening 15 extending through the floor of the boot near the forward end thereof. The movement of the glass through the outlet opening is controlled 35 by a pair of regulating devices each comprising a head or block 16 of fire clay or other refractory material and a stem 17.

Metal reinforcing rods 18 extend through 40 the stem 17 and provide means for the attachment of lever arms 19 and 20. Said arms are fulcrumed on a pivot pin 22 mounted in a bearing bracket 23 attached to a frame 24 which supports the boot 12. The levers 19 and 20 comprise arms 25 and 26 respectively, extending upward and carrying cam rolls 27 which run on cams 28 and 29 mounted on a continuously rotating cam 45 shaft 30.

Motion is transmitted to the cam shaft 50 from a drive shaft 32 through gears 33 and 34, shaft 35 and gears 36, 37. The rolls 27 are held against their cams by coil 55 springs 38 mounted on a rod 39 extending

between the arms 19 and 20. The glass flows from the furnace to the outlet through channels 40 on opposite sides of a partition wall or island 42 rising from the floor of the boot. A burner 43 directs a flame 60 through an opening 44 extending forward and upward through the wall 42, thereby keeping said wall hot and also supplying heat to the space over the glass within the boot. 65

In operation, the cams 28 and 29 swing the levers 19 and 20, thereby moving the blocks 16 toward and from each other. As said blocks swing together, they exert an expelling force on the glass between them, 70 causing the glass to issue from the outlet orifice in the form of a suspended gob which is then severed by shears 45 operated automatically in synchronism with the movements of said blocks. After a gob is severed, the blocks swing apart to the Figure 75 4 position. This movement causes an upward pull on the glass, counteracting the action of gravity and retarding the glass. The upward pull may be sufficient to draw 80 the glass back into the outlet. The inner faces of the regulating blocks 16 may be made concave, as shown at 46, to form a cup-shaped space when said blocks are together. By thus shaping the blocks, a comparatively 85 large quantity of glass is embraced between them and the expelling action on the glass is increased. The space between the blocks also provides a reservoir from which the discharge of glass may continue after the 90 blocks 16 have been brought together.

Modifications may be resorted to within the spirit and scope of my invention.

What I claim is:

1. A glass feeder comprising, in combination, a receptacle to contain molten glass and provided with a discharge orifice, and means controlling the discharge of glass through said orifice comprising mechanical members within the glass adjacent to the orifice, and automatic means for periodically moving said members toward and from each other in a direction transverse to the direction of movement of glass through the orifice. 95

2. A glass feeder comprising, in combination, a receptacle to contain molten glass and provided with a discharge orifice, and means controlling the discharge of glass through said orifice comprising mechanical 100 members within the glass adjacent to the orifice, and automatic means for periodically moving said members toward and from each other in a direction transverse to the direction of movement of glass through the orifice. 105

members within the glass adjacent to the orifice, and automatic means for periodically moving said members toward and from each other in a direction transverse to the direction of movement of glass through the orifice, said members when moved toward each other serving to substantially cut off the flow toward said orifice.

3. The combination of a container for molten glass having a discharge orifice below the level of the glass, means to control the discharge of glass therethrough, said means comprising a mechanical member within the glass adjacent the orifice, means for periodically reciprocating said member in a direction transverse to the direction of movement of glass through the orifice, and means cooperating with said member to substantially close the orifice 20 while said member is at the limit of its movement in one direction.

4. Glass feeding apparatus comprising, in combination, a receptacle for molten glass having an outlet opening, means to regulate the discharge of glass through said opening comprising a pair of mechanical members projecting into the glass, and means to move said members toward and from each other in a direction transverse to the movement of the glass through the opening.

5. Glass feeding apparatus comprising, in combination, a receptacle for molten glass having an outlet opening, mean to regulate the discharge of glass through said opening comprising a pair of mechanical members projecting into the glass, and means to move said members toward and from each other in a direction transverse to the movement of the glass through the opening, said members being symmetrical with respect to the axis of said opening.

6. Glass feeding mechanism comprising, in combination, a receptacle for molten glass having a discharge opening in the bottom thereof, means to control the discharge of glass through the opening comprising a pair of heads within the glass over the opening, and means to reciprocate said heads horizontally and cause them to periodically meet over said opening.

7. Glass feeding mechanism comprising, in combination, a receptacle for molten glass having a discharge opening in the bottom thereof, means to control the discharge of glass through the opening comprising a pair of heads within the glass over the opening, and means to reciprocate said heads horizontally and cause them to periodically meet over said opening, said heads being positioned when brought together to substantially cut off the supply of glass to the opening.

8. Glass feeding mechanism comprising, in

combination, a receptacle for molten glass 65 having a discharge opening in the bottom thereof, means to control the discharge of glass through the opening comprising a pair of heads within the glass over the opening, and means to reciprocate said heads horizontally and cause them to periodically meet over said opening, said heads having their meeting faces recessed to form a reservoir in communication with the discharge opening.

9. Glass feeding mechanism comprising, in combination, a receptacle to contain molten glass provided with an outlet opening in the bottom thereof, regulating means comprising heads within the glass over said opening, lever arms carrying said heads, cams operative to periodically actuate said arms and thereby horizontally reciprocate said heads in the glass in a direction transverse to the flow of glass through the opening and cause them to meet over said opening, and means to effect a relative adjustment of the cams and thereby adjust the meeting position of said heads.

10. In glass feeding mechanism, the combination of a furnace, a forehearth or extension projecting therefrom in which a continuous supply of molten glass from the furnace is maintained, said extension including a cover providing a confined space over the glass, said extension having an outlet opening in the bottom thereof adjacent its outer end, an island projecting upward in the boot between aid opening and the furnace, said island having a passageway therethrough opening into the interior of the forehearth over the glass, and a burner for supplying burning gases through said passageway into said confined space.

11. In glass feeding mechanism, the combination of a furnace, a forehearth or extension projecting therefrom in which a continuous supply of molten glass from the furnace is maintained, said extension having an outlet opening in the bottom thereof adjacent its outer end, an island projecting upward in the boot between said opening and the furnace, said island forming with the forehearth, separate channels through which the glass flows to the said outlet, regulating means controlling the discharge of glass through the outlet comprising mechanical controlling devices projecting into the glass at the forward end of the forehearth, and means to periodically reciprocate said devices and cause them to meet over the outlet, said devices being arranged to control the supply of glass through the respective channels.

Signed at Toledo, in the county of Lucas and State of Ohio, this 15th day of May, 1923.

LEONARD D. SOUBIER
